MORRIS H. BENNETT, OF WATERBURY, CONNECTICUT, ASSIGNOR, BY MESNE ASSIGNMENTS, TO MOTO METER GAUGE & EQUIPMENT CORPORATION, OF LONG ISLAND CITY, NEW YORK, A CORPORATION OF DELAWARE

ACOUSTIC SIGNAL MECHANISM

Application filed December 22, 1928. Serial No. 327,829.

This invention relates to an improvement in acoustic signal mechanism and particularly to such a mechanism for use on automobiles and other vehicles.

One object of the present invention is to provide an electrically actuated signal mechanism which will be very efficient from the standpoint of current consumption.

Another object is to provide a construction such that the sound emitting device may be conveniently mounted at the front of an automobile while at the same time not requiring heavy fastening means.

With these general objects in view and some others which will be obvious to those skilled in the art from the description hereinafter, the invention comprises the features, details of construction and combination of parts which will first be described in connection with the accompanying drawings and then more particularly pointed out.

In the drawings,

Fig. 1 is a front elevation illustrating the preferred embodiment of the invention and the manner of mounting it at the front of an automobile, a cross-bar at the front of an automobile being shown in part.

Fig. 2 is a side elevation of the same mechanism.

Fig. 3 is a sectional view on the line 3—3, Fig. 1.

Fig. 4 is a detail section on an enlarged scale illustrating one form of make and break device which may be used.

Referring to the drawings and particularly Fig. 3, 1 is a cup-like device of magnetic material having an arm 2 extending from the cup, this arm being formed, in the present example, by slitting the side of the cup and bending the metal outward, as will be clear from the drawing. At the center of the cup there is mounted a core 3 of magnetic material, which may be secured to the cup in any suitable way, as for example by forming the core with a reduced portion at one end, inserting this through a hole in the wall of the cup 1, and then riveting the projecting end of the core. In the annular space between the core and cup is placed a winding 4, the axis of which is coincident with the

principal axis of the core, that is, the planes of the individual spirals are transverse to the said principal axis of the core. It will be seen that the cup 1, the core and the winding 4 constitute an armor-clad electro-magnet. This electro-magnet is arranged to coact with a suitable armature 5, which in the present instance is a disk of substantially the same diameter as that of the cup 1, this armature being of magnetic material. The electro-magnet and its armature are located within a chamber formed by two members, each of which constitutes a sound-producing diaphragm. These diaphragm members are indicated at 6 and 7 respectively. In the present example, each member comprises a disk portion 6a, 7a, a flange portion 6b, 7b, and a sloping portion 6c, 7c connecting the disk portion and the flange portion. The flange portions of the two members are held together in any suitable way so as to make a waterproof joint. In the preferred embodiment of the invention as illustrated in Fig. 3, the flanges engage a ring 8 and are clamped tightly to the ring by screw-headed bolts 9 provided with nuts, these bolts extending through the flanges and the ring, each bolt also extending through a tubular spacing post 10, and through the wall of a rear casing member 11. The ring 8 may be of any suitable material, but most advantageously is of compressible material such as rubber, suitably treated paper, or fiber, so as to form a waterproof gasket between the flanges of the diaphragm members 6 and 7.

The electro-magnet is secured to one of the diaphragm members and the armature to the other. In the best embodiment of the invention, the electro-magnet, being heavier than the armature is secured to the rear diaphragm member 6 by means of screws, as indicated at 12, while the armature is secured to the front diaphragm member 7, by screws, as indicated at 13. The rear diaphragm member 6 has two eyelets 14 and 15 through which pass the respective electric conductors 16 and 17 forming part of the electric circuit for energizing the electro-magnet. The eyelets fit tightly around the conductors so that there is no danger of leakage around them. The eyelets 100

may be of suitable insulating material if desired. To the arm 2 of the magnet are secured a pair of spring contact devices, these being suitably insulated from each other and from the arm 2. In the present embodiment of the invention, one spring contact device, indicated at 18, is longer than the other one, 19, as will be clear from the drawing, Fig. 4. Between the spring contact device 18 and the arm 2 is placed a block 20 of insulating material, and between the two contact devices 18 and 19 is placed a similar block 21 of insulating material. Screws 22 passing through holes in the contact devices and through the insulating blocks, are screwed into the arm 2, thereby clamping all the parts together. The screws do not make contact with the contact devices 18 and 19 but are suitably bushed where they pass through the holes in said contact devices. Each contact device has a contact point, as indicated at 23 and 24 respectively, these cooperating to close the electric circuit. The contact devices are included in a circuit with the winding 4 of the electro-magnet. In the present example the longer contact device 18 is connected by a conductor 25 to one end of the winding 4, whose other end is joined to a conductor 16 which passes through the eyelet 14 and thence through an eyelet 27 in the rear casing member 11. To the other contact device 19 is secured a conductor 17 which passes through the eyelet 15 and thence through said eyelet 27 in the rear casing member 11. The two conductors 16 and 17 when the apparatus is installed, will be connected to the terminals of a source of electricity, as for example a battery as indicated at 29, Fig. 4, the circuit including a switch device of a suitable nature, as for example the spring push button switch indicated diagrammatically at 30, Fig. 4. The front diaphragm member, 7, carries an abutment screw 31 which is threaded through a nut 32 soldered to the diaphragm member 7. The end of this abutment screw 31 is arranged to encounter the projecting end of the longer contact device 18, when the diaphragm members move toward each other, as more fully explained hereinafter, whereby the contact points 23 and 24 are separated from each other.

To the rear member 11 of the casing a front member 33 is secured by any suitable means, as for example the bolts 34 passing through the flanges of the casing members. While the front member of the casing may be shaped in various ways, it is advantageous with the present construction to avoid the use of a horn, because this at the front of an automobile would catch the blast of air and concentrate it on the front diaphragm, which at the high speeds of an automobile would give pressures on the front diaphragm such as would be likely to injure it.

65 To avoid any possibility of this the front

member 33 of the casing in the best embodiment of the invention is made generally convex outward so that it has a tendency to deflect the air outward away from the center of the front member. At the same time, in order to provide for the escape of the sound waves produced by the diaphragm members suitable openings or windows are made in the front member 33 of the casing, these openings not being at the center. In the structure 70 illustrated in the drawings, the front member 33 has a raised central portion connected by a substantially cylindrical portion with a sloping or coned portion which in turn merges into first a cylindrical portion and 75 then a flanged portion as will be clear from the drawings.

The coned portion is provided with the outlets or windows. On account of the stiffness of the front member 33 due to its cylindrical portions the air blast due to the forward movement of the vehicle is deflected and tends to flow at an angle across the outlets or windows, so that to only a small extent 80 can the air blast reach the front diaphragm member of the sound-emitting mechanism.

85 For the purpose of securing the acoustic signalling device to the front of an automobile, it is secured to a suitable holder, which in the present embodiment of the invention 90 comprises a plate 35 held to the lower part of the casing members 11 and 33 by bolts 34 and screws 37. The plate 35 has a groove to receive the cross-bar of the automobile, this bar being indicated at X, Figs. 1 and 2. 95 To the plate 35 is secured a cap 38 which also has a groove to receive the cross-bar. The cap 38 is bolted to the plate 35 by screw-headed bolts as indicated at 39, and when 100 these are drawn up tightly the holder and the signalling device carried by it are clamped to the cross-bar X. It is obvious that the air-blast due to the motion of the automobile will, by its pressure on the signalling device, create a torque on the cross-bar and in time may tend to cause the holder to slip on the cross-bar. To overcome this 105 the holder is arranged to support a pressure-balancing device below the signalling device. Since a license-tag or plate must be carried 110 at the front of the vehicle, it is advantageous to employ this tag as the pressure-balancing device and therefore the holder is arranged to support this tag below the signalling device. However, as the area of the tag 115 may be different from the effective area of the signalling device, the holder is so arranged that the lever arm of the license tag may be less than that of the signalling device, whereby it becomes possible to make 120 the torque due to the wind pressure on the license tag equal and opposite to the torque due to the wind pressure on the signalling device. In the present example, the holder 125 is provided with a horizontal member 40 130

along its lower edge and close to the cross-bar, this horizontal member having slots to receive bolts 41 which hold the license-tag in place.

In operating the signalling device the electric controlling circuit is closed by closing the switch. This energizes the electro-magnet and causes an attraction between the magnet and armature, whereby the diaphragm members 6 and 7 are caused to approach each other. After a short travel toward each other, the end of the abutment screw, 31, engages the projecting end of the longer spring contact device, 18, and causes the contact point of the latter to be separated from the contact point of the contact device 19, thereby opening the electric circuit. The electro-magnet is thereby de-energized and the diaphragm members, by virtue of their resiliency are set in vibration. As soon as they move away from each other, the contact points close the circuit again and the operation then continues as before explained. Owing to the difference in weights between the electro-magnet and its armature the tones emitted by the two diaphragm members may be different, but the difference in tones may be modified by a proper selection of the relative thickness and resiliencies of the two diaphragm members. Also the respective weights of the armature and of the electro-magnet may be varied within reasonable limits. In this way, the two tones emitted may be predetermined so as to blend in the desired way to give a satisfactory signalling note.

It will be noted that the electro-magnet and its armature constitute a highly efficient motor device for operating the diaphragms, because there is a relatively short magnetic circuit with an air gap of low resistance.

What I claim is:

1. A holder for an automobile horn arranged to be secured to the front cross-bar of an automobile, said holder having means for holding an automobile license tag below the cross bar and also means for holding an electrically-controlled sound-emitting device above the cross bar, the distances, from the cross-bar, of the centers of effective wind-pressure on the tag and signalling device respectively being such as to cause a substantial equalization of the two opposing torques due to said wind-pressures.

2. In combination with a signaling device adapted to be mounted on a substantially horizontal fixture on an automobile vehicle in a position subject to wind pressures tending to create a torque on the fixture, a holder comprising a split plate secured to the signaling device above the fixture and having a portion extending below the fixture, fastening means for clamping said plate tightly around the fixture, and a bracket on the por-

tion of said plate below the fixture to receive a pressure balancing device to overcome the torque created on the fixture by the pressure on the signaling device.

In testimony whereof, I have hereunto set my hand.

MORRIS H. BENNETT.
